UNITED STATES PATENT OFFICE.

GEORGE M. CLARK, OF BATTLE CREEK, MICHIGAN.

BOAT.

1,258,745.

Specification of Letters Patent. Patented Mar. 12, 1918.

Application filed March 8, 1917. Serial No. 152,608.

To all whom it may concern:

Be it known that I, GEORGE M. CLARK, a citizen of the United States, residing at Battle Creek, in the county of Calhoun and 5 State of Michigan, have invented certain new and useful Improvements in Boats, of which the following is a specification.

The present invention relates to boats, and more particularly has reference to a sectional nesting boat, chief among the objects of which is to construct a boat of the character set forth that may be readily assembled or dismantled, and capable of being nested to occupy space sufficiently small to permit 15 of its being carried on the footboard of an ordinary automobile; whereby the same will be rigid when assembled, neat and tasty in appearance, simple in construction, and capable of being manufactured at a minimum 20 expense. Briefly, the present invention comprises a boat, the abutting compartments of which are held in locked contact at their sides by means of metallic clips through which bolts connect the sides thereof, intermediate 25 compartments having at least one of their ends formed with a recess into which a tongue from an abutting compartment may be inserted and held in locked engagement by means of metallic clips fitting within depressions in the boat bottom sections and 30 secured by bolts and nuts, the nuts of which fit within pockets of said depressions and over which retaining straps are fitted. To this end the invention consists in the arrangement and combination of parts as hereinafter more fully described and pointed out in the appended claims.

Referring to the drawings, Figure 1 is an embodiment of my invention in plan view.

40 Fig. 2 is an inverse view of the same.

Fig. 3 is a side elevation.

Fig. 4 is an enlarged cross section of Fig. 2 on the line $\alpha-\alpha$, looking toward the right.

Fig. 5 is a longitudinal vertical section.

45 Fig. 6 is a side elevation of an automobile with my improved boat nested and resting edgewise and secured to the stepboard of the same by means of straps, as shown.

Fig. 7 is a detail longitudinal section of 50 the jointing tongue of a boat compartment.

Fig. 8 is a detail vertical longitudinal section, in modification, of the boat at the junction of two of its compartments at a point where a bottom connecting clip is attached.

55 Fig. 9 is a detail longitudinal section of an intermediate compartment at its end,

showing a nut within its pocket, and its retaining strap preparatory to being closed over said nut.

Fig. 10 is an enlarged detail vertical longitudinal section of abutting boat compartments at a point where a bottom connecting clip is affixed, and shows said clip, its bolts with nuts, the nut retaining straps, the slip tongue and the recess in the boat and tongue for receiving the clip.

In the drawings forming a part of this specification, like marks of reference refer to corresponding or equivalent parts in the several views, in which A, B and C, represent abutting compartments of a boat; D, a centrally-disposed portable seat; and E, a portable interchangeable seat.

In describing my invention, I will confine myself more particularly to boats constructed of sheet metal, although not limiting the adaptability of its peculiar construction to any particular material, as it would be obvious that a boat could be constructed of material other than metal and still retain the characteristics of my invention; likewise, in lieu of a boat comprising but three detachable compartments, more compartments might be used if deemed expedient. In the present instance an intermediate compartment B is formed with a longitudinal clearance between its end partitions 1-1 sufficient to permit the stern compartment A, including its slip tongue 2, to fit and nest therein, the said stern compartment likewise having a clearance between its partition 3 and rear end 4 to permit the bow compartment C, together with its slip tongue 5, to nest therein, as shown in Fig. 6. In forming the several compartments, the arrangement is such that the breadth of alternating abutting end portions will be wider than succeeding nesting compartments, as, for instance, the abutting end of the compartment A is wider than the abutting end of the compartment C adapted to nest therein.

In the drawings, the boat is formed with flaring sides with rounding bottom edges, and its compartments have a stiffening marginal hem 6 formed by rolling the metal outwardly and soldering or otherwise attaching its depending edge 7 to the sides of the sections. The partitions of the several compartments may be attached to the sides after bending the ends to lie in contact therewith by either welding, riveting or other

means, as shown in Figs. 1 and 6, or by means of separate angular pieces, as 8, at the junction of the parts, as in Figs. 4, 5 7 and 8, in like manner, or both, as expedient. To the stern of the boat a seat F is attached by suitable hinges 9 to the end 4, appropriate ledges being fitted within the boat on which the seat may rest. An object in hinging the seat being to afford 10 means for readily permitting the bow section to be placed therein when nested for storage, crating or overland transportation.

To tie the abutting compartments along their sides, metallic clips 10 are provided. 15 These clips have holes in their extremities through which screw-headed bolts 11 engage nuts 12 on the interior of the boat through registering holes in the sides thereof. The compartments of the boat are secured in contact on its bottom by means of metallic clips 13 spanning its abutting sections. These clips are fitted within recesses 20 for the purpose of presenting a smooth uniform surface on the boat bottom, the clips 25 being held by means of bolts and nuts in a manner very similar to the clips 10 on the boat sides.

In the modification shown in Fig. 8, the sections B and C abut and are attached together on their bottoms by means of clips, as 18, a groove, as 15, indented longitudinally within the ends of the abutting sections on their bottoms for receiving said clips, said recesses being still deeper recessed to form offset caps 17 for receiving the nuts 18, which also prevent said nuts from turning when the bolts, as 19, are screwed to place. That the nuts 18 may be placed or removed as occasion may require, 40 a metallic strap 20 is soldered, riveted or otherwise attached at one end of the recess 15, its opposite end extending along said recess between the boat bottom and the connecting clip 18, and fitted over the nut covering caps 21, are soldered to prevent water 45 from entering the boat.

An embodiment for holding the abutting sections of the boat together is still further shown in detail in Fig. 10, said figure being representative of an intermediate and bow compartment of a boat, after the principle shown in Fig. 1. In this figure the tongue 5 is shown within the recess 15 formed in the section B. In other respects 55 the method for securing the clips 13 is substantially like the method shown in Fig. 8, except that on the intermediate section B the strap 20 lies between the tongue 5 and the recessed bottom of the boat.

60 In Fig. 7 is shown an embodiment of the slip-tongues 2 and 5, in which the boat bottom 14 projects beyond the partition 3 and is reinforced by a strip 24 folded longitudinally thereover, the parts being formed in 65 alinement at the bottom, reinforcing angle

pieces 8 being fitted either side of the partition 3 and engaging said tongue and boat bottom, respectively.

The boat compartments may be braced in any suitable manner as, for instance, by 70 braces 22 of so-called commercial half-round iron bent into requisite form and riveted or otherwise attached to the boat.

The seat E is interchangeable in its position within the boat and it is fitted over the 75 abutting partitions of its compartments. As shown, it is placed near the bow and is held in position by means of depending clasp members 23 secured underneath the seat and formed to clasp the inner walls of said 80 partitions, the clasp members also tending to clamp the boat compartments in locked engagement.

A boat constructed as thus shown and described is not only light to handle when assembled, but capable of being dismantled or assembled by an artisan of ordinary ability, and without especial tools for the purpose, 85 tasty in design, and capable of being nested in small compass to meet the requirements 90 of those wanting an inexpensive boat which is at the same time commodious and well fitted for the various purposes for which a boat of this character can be used.

Having, therefore, described my invention, what I claim as new and desire to secure by Letters Patent, is:

1. A boat consisting of abutting detachable compartments, one being adapted to receive another in which successive compartments are fitted, side clips spanning said abutting compartments on their sides, and bottom clips spanning said compartments on their bottoms, bolts passing through said clips and said abutting sections and nuts 105 run on said bolts to secure said assemblage of parts intact.

2. A boat consisting of abutting detachable compartments, intermediate compartments of which are formed with a recessed bottom at one end and a tongue at the opposite bottom end, abutting sections of which are correspondingly formed, the tongue of one section engaging the recessed bottom of its abutting section, means for 110 detachably connecting said sections, one section being adapted to receive another in which successive compartments are fitted.

3. A boat consisting of abutting detachable compartments, an intermediate compartment having recessed bottom ends, abutting compartments, each of said compartments having a tongue engaging the recessed end portions of said intermediate compartment, one section being adapted to 120 receive another in which successive compartments are fitted, and clips spanning the abutting end compartments of said boat, and bolts passing through the ends of said clips and the bottom of said compartments, 125 130

and nuts run on to the threaded ends of said bolts, and caps fitted over said nuts.

4. In a boat, the combination with the partitions of abutting end sections and a seat fitting over said partitions and fitted with depending clasping members engaging said partitions therebetween, substantially as and for the purpose set forth.

5. A boat consisting of abutting detachable compartments, an intermediate compartment having recessed bottom ends, abutting end compartments having a tongue at one end thereof engaging a recessed end of said intermediate compartment, side clips connecting said abutting compartments near the side edges and bottom clips connecting said compartments on their bottoms, one compartment being adapted to receive another in which successive compartments are fitted.

6. A boat consisting of detachable compartments, the partitions of each compartment intermediate of the ends of the boat adapted to abut, a seat fitted over the abutting partitions of opposite compartments, clips depending from said seat and engaging the opposite sides of said abutting partitions, an intermediate compartment having recesses at its end, abutting end compartments having a tongue at one end engaging a recessed end of said intermediate compartment, side clips connecting said compartments near their side edges, and bottom clips connecting said compartments at their abutting sides, one of said compartments adapted to receive another compartment in which successive compartments are fitted.

7. A boat consisting of abutting detachable compartments, one compartment of which is adapted to receive another in which successive compartments are fitted, side clips connecting said compartments at their abutting ends near their side edges, the abut-

ting ends of said compartments having longitudinal registering recesses on their bottoms, nuts fitted in depressions at the closed ends of said recesses, straps affixed at one end in said recesses over said nuts and bent at their opposite ends to lie between the abutting ends of said compartments, clips fitted in said recesses over said straps and bolts passing through said clips and straps and screw-threaded into said nuts, substantially as and for the purpose set forth.

8. A boat consisting of abutting detachable compartments, an intermediate compartment having recessed bottom ends, abutting end compartments having a tongue at one end thereof engaging a recessed end of said intermediate compartment, said tongue comprising a continuation of the bottom of its compartment, and a strip of sheet metal folded to envelop the same over its end and both sides and terminate flush with the bottom of said compartment, said intermediate compartment adapted to receive another compartment in which successive compartments are fitted, and means to detachably connect said compartments.

9. A boat consisting of abutting detachable compartments, one compartment of which is adapted to receive another in which successive compartments are fitted, said compartments having their side edges formed with a roll terminating in a hem riveted or otherwise attached to the sides, clips spanning abutting compartments at both their bottoms and sides, bolts passing through said clips and fitted with nuts to secure said compartments intact, for the purpose set forth and described.
